DESIGN FOR A TEXTILE FABRIC SUITABLE FOR BLANKETS OR SIMILAR ARTICLE

John R. Morgan, Oak Park, Ill., assignor to Sears, Roebuck and Co., Chicago, Ill., a corporation of
New York

Application January 29, 1937, Serial No. 67,330

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Textile Fabric Suitable for Blankets or Similar Article, of which the following is a specification, reference being had to the accompanying drawing, forming a part thereof.

The drawing is a plan view of a textile fabric suitable for blankets or similar article embodying my new design.

I claim:

The ornamental design for textile fabric suitable for blankets or similar article, as shown.

JOHN R. MORGAN.
